UNITED STATES PATENT OFFICE.

HARRY B. McNULTY, OF WASHINGTON, DISTRICT OF COLUMBIA, ASSIGNOR TO THE McNULTY INCANDESCENT GAS LIGHTER COMPANY, A CORPORATION OF THE DISTRICT OF COLUMBIA.

AUTOMATIC GAS-IGNITER.

SPECIFICATION forming part of Letters Patent No. 773,410, dated October 25, 1904.

Application filed October 22, 1903. Serial No. 178,092. (No model.)

To all whom it may concern:

Be it known that I, HARRY B. McNULTY, a citizen of the United States, residing at Washington, in the District of Columbia, have invented certain new and useful Improvements in Automatic Gas-Igniters; and I do hereby declare the following to be a full, clear, and exact description of the invention, such as will enable others skilled in the art to which it appertains to make and use the same.

It is the common practice to revolve the valve of a gas-light by means of electrically-actuated mechanism; but these structures usually involve a valve actuated by a step-by-step movement and an igniter producing a series of sparks by a vibrating movement tending to shake and jar the surrounding parts, wherefore it has been found difficult to automatically ignite a gas-lamp provided with a mantle, and by the present improvements I contemplate providing means for automatically actuating the valve of a gas-supply pipe and lighting the charge escaping therefrom without vibration of the parts.

In carrying out the invention I propose to assemble electromagnets and armatures therefor in such correlation to levers and a controlling-valve as to effect movement of such valve relative to the particular magnet energized, suitable means being provided for igniting a charge of gas.

The invention consists in certain novel constructions, combinations, and arrangements of parts, as will be hereinafter fully described and claimed.

In the accompanying drawings, Figure 1 represents a longitudinal vertical central section taken through the casing of an automatic igniter embodying the features of the present invention, illustrating the improved elements in elevation, the circuits being disclosed conventionally. Fig. 2 represents a horizontal transverse section taken on the plane of line 2 2 of Fig. 1. Fig. 3 represents a view similar to Fig. 1 of a slightly-modified form of the same. Fig. 4 represents a horizontal transverse section taken on the plane of line 4 4 of Fig. 3.

Referring to the drawings by numerals, 1 indicates any common form of gas-supply tube provided with a suitable plug-valve 2, arranged in a valve-casing 3, interposed in the length of said tube 1. The valve 2 may be formed with a longitudinally-extending projecting rod 4, extending through the casing 3 and normally retained against a bearing-stud 5 by means of a spring 6 coiled about said rod and engaging a ring 7, carried by the outer end thereof. The valve 2 is thus positively retained in its seat and is at the same time left free to rotate for opening and closing the passage or tube 1. Carried by the tube 1 is a suitable base-plate 8, which plate carries a standard 9, supporting the stud 5. Mounted on the base-plate 8 at opposite sides of the valve 2 are suitable electromagnets 10 and 11. While I have illustrated two magnets 10 and two magnets 11, it will be understood that any number may be employed, as may be found desirable.

The valve 2 is provided with a suitable stem 12, carrying a crank 13, provided with a wrist-pin 14. A yoke 15 surrounds the tube 1 above the upper ends of magnets 10 and 11, and said yoke consists of a bar 16, extending transversely across the tube 1 on two opposite sides thereof and having their ends connected by armatures 17 and 18, the armature 17 being positioned to be effected by the flux of magnet 10 and the armature 18 being arranged just above the magnets 11. Each bar 16 is provided with a pivot-point 19, extending inwardly from the central portion thereof and engaging a notch or indentation formed in the tube 1, whereby the yoke 15 is supported and left free to swing vertically. An operating-rod 20 depends centrally from the bar 16 on that side of tube 1 corresponding with the crank 13, and said bar is formed at its lower end with an elongated notch or slot 21, adapted in operation to engage wrist-pin 14 for actuating the valve 2 relative to the swing of the yoke 15.

The plate 8 carries a suitable insulating-block 22, upon which block is arranged a plate 23, carrying a lever 24, pivotally connected

therewith. The lever 24 is provided at its upper end with an insulating-block 25, formed with an open slot or a longitudinal notch 26, inclosing a pin 27, projecting laterally from rod 20. Extending transversely of and connected to the lever 24 are contact-brushes 28 and 29, designed in operation to contact with posts 30 and 31, the post 31 extending through said block and being provided at its lower end with binding-nuts 32 for receiving the conductor 33, leading to the resistance 34, grounded by a conductor 35 on the tube 1. A conductor 36 leads from the plate 23 to and connects with a binding-post 37, carried by 15 and insulated from a plate 8, a conductor 38 connecting said binding-post with any suitable form of switch 39. (Illustrated conventionally in the accompanying drawings.) A conductor 40 is designed to connect the switch when closed with one pole of battery 41, the opposite pole of said battery being grounded by a conductor 42 on the tube 1. The conductor 43 connects with the post 30 and with the windings of magnets 11, the opposite ends of said windings being grounded by conductor 44 on the plate 8.

A binding-post 45 is carried by plate 8 and insulated therefrom and is connected with a conductor 46, extending to a switch 47, designed to contact with wire 40. A conductor 48 connects with post 45 and extends to one end of the windings of magnets 10, the opposite end of said magnet-windings being grounded on the plate 8 through a conductor 49.

35 In operation, the parts being in the position illustrated in Fig. 1, the switch 39 is closed, whereupon current starting from the battery 41 flows through conductor 40, switch 39, and conductor 38, binding-post 37, conductor 36, plate 22, lever 24, brush 28, post 30, conductor 43, the winding of magnets 11, conductor 44, plate 8, tube 1, and conductor 42 to the battery. The flux of the magnets 11 thus energized affects armature 18 and swings yoke 15 upon its pivots, whereby bar 20 is thrown from the position indicated in Fig. 1 to a corresponding incline on the opposite side of the axes of rotation of valve 2, whereby said valve through the movement of the crank 13 under 45 the action of bar 20 is thrown to an open position, permitting a charge of gas to pass through the tube 1 to a burner or set of burners, where the same is electrically ignited, resulting from the following described operation: When the parts are in the position indicated in Fig. 1, the brush 28 contacts with post 30; but when said parts are swung to the position just described the brush 29 is caused to contact with post 31 and the contact between brush 28 and post 30 is broken, whereby the circuit will be changed so that electricity flowing from battery 41 will move through conductor 40, switch 39, conductor 38, binding-post 37, conductor 36, plate 23, lever 24, brush 29, post 31, conductor 33, re-

sistance 34, conductor 35, tube 1, and conductor 42 to the battery. Here it is to be observed that the resistance 34 may be of any preferred material; but I usually employ platinum and position the same at a suitable point 70 relative to the point of discharge of gas for igniting the same as soon as the platinum becomes incandescent, owing to the excessive amperage forced therethrough. After the gas is lighted the said switch may be opened. 75 When it is desired to extinguish the light or lights supplied with gas through tube 1, it is only necessary to close switch 47, whereupon current flowing from battery 1 through conductor 40 will move through switch 47, 80 conductor 46, binding-post 45, conductor 48, the windings of magnets 10, conductor 49, plate 8, tube 1, and conductor 42 to the battery. The magnets thus energized effect the armature 17 and swing the yoke 15 back to 85 the position indicated in Fig. 1, whereby the supply of gas through tube 1 is cut off.

In Figs. 3 and 4 of the accompanying drawings I have illustrated a slightly-modified form of the present improved structure, said modification consisting, chiefly, in the dispensing with one of the contact-posts and the corresponding brush carried by the lever actuated by the valve-operating bar. Referring to said figures in particular, 50 indicates a suitable gas-supply tube having such supply controlled by valve 51, rotatably mounted in its casing 52, interposed in the length of said tube. The valve is operated in a manner precisely similar to the operation of valve 100 2 and with corresponding elements, including the lever 53, pivoted to a contact-plate 54, actuated by a bar 55, carried by yoke 56. The yoke 56 is controlled by sets of electromagnets 57 and 58. The plate 54 is carried by an insulating-block 57', supported by a base-plate 58', carried by tube 50. A post 59 rises from the insulating-block 57' in position for contacting with a brush 60, carried by lever 53. A binding-post 61 extends through block 105 57' and plate 58' and engages plate 54, a conductor 62 engaging said binding-post and extending to a resistance 63, connected with a conductor 64, grounded on tube 50. The resistance 63 is preferably a platinum igniter 110 and in operation is positioned in such relation to the discharge from tube 50 as to ignite the same. A conductor 65 leads from conductor 62 to a switch 66, which switch is adapted to be operated for closing contact with the conductor 67, leading to one pole of battery 68, the opposite pole of said battery being grounded by a conductor 69 on tube 50. A conductor 70 connects with post 59 and with one end of the windings of magnets 58, the 115 opposite ends of said windings being grounded on the plate 58 through conductor 71. The conductor 72 connects one end of the windings 57 with a binding-post 73, said binding-post being connected by a conductor 74 with 120 125 130

a switch 75, adapted to close contact with conductor 67. When it is desired to open the valve 51 and ignite the charge of gas passing through the tube 50, the switch 66 is closed, 5 whereupon current flowing from battery 68 passes through conductor 67, switch 66, conductor 65 and divides upon arriving at the conductor 62, part of said current passing through resistance 63, conductor 64, tube 50, 10 and conductor 69 to the battery 68. However, the resistance 63 is as great or greater than the resistance of coils 58, whereby the greater portion of the current will flow through conductor 62, binding-post 61, plate 54, lever 15 53, brush 60, contact-post 59, conductor 70, the windings of magnets 58, conductor 71, plate 58', tube 50, conductor 69 to the battery. The magnets 58 thus energized will cause the yoke 56 to swing and throw the lever 53 to 20 one side, breaking contact between brush 60 and post 59, whereupon the valve 51 will be opened, owing to the action of rod 55, and the entire current will be caused to flow through conductor 62 and resistance 63 and 25 back to the battery. The entire current passing through the resistance will raise the same to incandescence and ignite the charge passing from tube 50, it being understood that the resistance 63 may consist of as many 30 platinum igniters as may be desired for igniting a cluster of lights or for igniting a single light, as preferred. When it is desired to extinguish the lights supplied from tube 50, it is only necessary to close switch 75, where- 35 upon current flows from battery 68 through conductor 67, switch 75, conductor 74, binding-post 73, conductor 72, the windings of magnets 57, plate 58', tube 50, and conductor 69 to the battery. The magnets 57 thus en- 40 ergized will affect the yoke 56 to tilt or swing the same back to the position formerly occupied and as illustrated in Fig. 3 of the drawings, whereupon the valve 51 will assume a closed position.

45 Having thus fully described my invention, what I claim as new, and desire to secure by Letters Patent, is—

1. In an automatic igniter, the combination with a supply-tube and a valve controlling the 50 passage of gas through the same, of an electromagnet, means actuated thereby for opening said valve, an electro-igniting device, a circuit for said electro-igniting device, and means for breaking the circuit of said magnet.

55 2. In an automatic igniter, the combination with a supply-tube and a valve carried thereby, of an electromagnet, means actuated thereby for opening said valve, an electric igniting device, a circuit for the same, a circuit for said 60 electromagnet including part of the circuit of said igniting device, and means actuated by said magnet for breaking the magnet-circuit.

3. In an automatic igniting mechanism, the combination with a supply-tube and valve 65 therefor, of an electromagnet, means actu-

ated thereby for opening said valve, an electro-igniting device, a circuit for said igniting device, and means actuated by said magnet for breaking the magnet-circuit and closing the igniting-device circuit.

4. In an automatic igniter, the combination with a supply-tube and a valve therefor, of an electromagnet, a circuit for said magnet, an armature for said magnet, means actuated thereby for throwing said valve, a contact- 70 post, brush, and lever interposed in the magnet-circuit, an electro-igniting device, a circuit therefor, and means actuated by said armature for moving said lever for breaking contact of said brush with said post.

5. In an automatic igniter, the combination with a supply-tube and a valve therefor, of a pivotally-mounted armature, an electromagnet for actuating the same, means carried by said armature for throwing said valve, a contact-post, a brush normally engaging the same, a circuit for said magnet including said brush and post, electro-igniting means, a circuit therefor, and means actuated by said valve-throwing means for breaking contact 80 of said brush with said post.

6. In an automatic igniter, the combination with a supply-tube and a valve therefor, of an electromagnet, an armature actuated thereby, means actuated by said armature for throwing said valve, contact-posts spaced apart, a brush designed to be brought into contact with said posts, an electro-igniting device, a circuit therefor including one of said posts and said brush, a circuit for said magnet includ- 95 ing the other post and the brush, and means actuated by said armature for moving said brush from contact with one of said posts to contact with the other thereof.

7. In an automatic igniter, the combination with a supply-tube and a valve therefor, of an electromagnet, an armature therefor, means actuated by said armature for throwing said valve, a brush, and means carried thereby engaging contacting means, a plurality of contacts for said brush, an electro-igniting device, a circuit for the same including one of said contacts and said brush, a circuit for said electromagnet including the other contact and said brush, and means guiding said brush from 110 one contact to the other under actuation by said armature.

8. In an automatic igniter, the combination with a supply-tube and a valve therefor, of an electromagnet, an armature therefor, a bar 120 actuated by said armature, means operated by said bar for throwing said valve, contact-posts spaced apart, a contact-brush designed to engage said posts, an electro-igniting device, a circuit therefor including one of said posts and said brush, and a circuit for said electromagnet including the other of said posts and said brush, said brush being adapted to be moved by said bar alternately into contact with said posts.

9. In an automatic igniter, the combination with a supply-tube and a valve therefor, of an electromagnet, an armature therefor, a bar actuated by said magnet, means actuated by said armature, and means actuated 30 by the armature for breaking the magnet-circuit and closing the circuit of the igniting device.
- 5 12. In an igniting mechanism, the combination with a plurality of electromagnets spaced 35 apart, of an armature for each of said magnets, a pivotally-mounted element connecting said armatures, an electro-igniting device, and means operated by said pivotally-mounted element for closing the circuit of said electro-igniting device and breaking the circuit 40 of some of said magnets.
- 10 13. In an igniting mechanism, the combination with a supply-tube, of a frame pivoted thereto, a valve-operating arm extending from 45 said frame, a plurality of armatures carried by the frame, an electromagnet for each of said armatures adapted to be alternately energized for swinging said arm, an igniting device, and means actuated by said arm for energizing 50 said igniting device.
- 15 In testimony whereof I hereunto affix my signature in presence of two witnesses.
- 20 25 HARRY B. McNULTY.
- Witnesses:
JOHN L. FLETCHER,
EDWIN E. VROOMAN.
11. In an igniting device, the combination with a pivotally-mounted armature, of an electromagnet adapted to actuate said armature when energized, an electro-igniting device, a circuit therefor, valve-operating means actu-
